WOMAN'S OVERSHOE

Stedman C. Pool, Essex, Conn., assignor to Essex Master Mold Co., Inc., Essex, Conn., a corporation of Connecticut

Filed Jan. 2, 1962, Ser. No. 68,148

Term of patent 3½ years

(Cl. D7—4)

Fig. 1.

Fig. 2.

Fig. 3.

Fig. 4.

FIG. 1 is a front perspective view of an overshoe embodying my new design;
 FIG. 2 is a side elevational view of the overshoe;
 FIG. 3 is a rear elevational view of the overshoe; and
 FIG. 4 is an elevational view, looking from the side opposite that shown in FIG. 2.

I claim:

The ornamental design for a woman's overshoe, as shown.
